UNITED STATES PATENT OFFICE.

ALOIS PIVETZ, OF FALL RIVER, MASSACHUSETTS.

JACQUARD WEAVING MACHINE.

Application filed May 24, 1927. Serial No. 193,904.

This invention relates to improvements in the jacquard weaving machine in which is applied an entirely new and different mechanism, especially with reference to a needle and hook arrangement, a needle safe-guard and in the construction of a machine in the form of a typewriter. The objects of the improvements are, first, to provide considerably shorter needles and hooks as compared with the usual make of machine of this character; second, an immediate adjustment of any part without hampering the production, and third, the reversing of the cylinder of the machine to any card desired.

As illustrated in the accompanying drawings;

Figure 1 is a side elevational view of the entire machine with the mechanism outwardly of the machine frame adjustable in the usual manner,

Figure 2 is a vertical cross sectional view of the machine showing a part of the mechanism within the machine frame,

Figure 3 is a plan view of the entire machine,

Figure 4 shows top plan and side views of the needle,

Figure 5 is a side view of a hook and needle with a hook holder and a needle holder, showing the action when the cylinder presses against the hooks,

Figure 6 is a front view of the hook holder and needle holder, and

Figure 7 is a cross sectional view of the entire needle and hook mechanism within the machine frame.

A frame A with ribs, rests upon the wooden support connected to the overhead beam and is built in typewriter form. This is, as here explained, of advantage in order to reach the various parts of the interior of the mechanism very easily without being forced to work from the top down as in the present type of machine.

The frame structure and associated mechanism which has been here chosen is in the most simple form and can be adjusted in any manner and by various methods now employed. The motion of the loom connection rods I and J as well as rods i_2 and i_3 , and j_2 and j_3 sets cylinder D and knives k_2 in corresponding motion. The cylinder D is held from the frame P which is attached to the frame A at p_3 , while knives k_2 are set in frame K which moves vertically by the shaft

S running through bearings A_1 and A_2 and screwed firmly to k_1 . The usual catch bar H turns the cylinder at d_1 while same is held in position through the hammer D_1 .

An important object of this invention is to provide a device to reverse the cylinder to any card desired and there is installed the cylinder reverser LL_1, l_2, l_3 , which pulled by the wire or rope l_5 , lets the reverse bar l_2 slide through the open support a_5 while nose l_3 lifts catch bar and slips onto the lantern d_2 to grip same and reverse the cylinder. Needless to say that the cylinder must be with its pegs d_4 out of needle board E before reversing.

The needle, as shown in Figure 4, consists of a straight wire or rod bent laterally at its outer end to the form of letter J and the doubled or folded portion bent upwardly and forwardly as shown at f. The needles are in groups of different lengths, the length increasing from the top to the bottom group or bank. Thus, assuming that the needles of the uppermost group or bank are of 4" length, the next group or bank (second row) will be of $1\frac{1}{8}$ " longer. This results in the declination of about 15 degrees. Instead of using, on the other end, a second needle board, the needle glides through and is easily held in the needle holders e.e₁. As shown in Figure 6, two strips of steel, one of $\frac{1}{8}$ " thickness and $\frac{1}{2}$ " width with notches just wide enough to allow for the needle, the other somewhat thinner and $\frac{3}{8}$ " wide are laid across the hook holder h_1 and fastened with the bolt e_2 , so as to accomplish a quick dismounting of any needle or an entire needle row. Compared with the present needles which are not less than 16" in length, the longest needle of this improved mechanism appears, as explained above, about $11\frac{1}{8}$ " in length. It is evident that this means saving on wire and as there is no pressure or friction, as on present machines through the springs, there is no risk of bending, which often results in loss of time through wearisome and expensive repairs.

The hook holder h_1 is disposed about $\frac{5}{8}$ " above the needle holder as illustrated in Figure 6 and is comprised of a thicker strip with notches h_3 rounded at the bottom to allow the hook and needle to ride unhampered through the notches. All of the hook holders h_1 are set into the frame A.

The hook G exactly bent as illustrated in Figure 5 is of $\frac{1}{8}$ " thickness which is suffi-

cient to stand the weight on the harness cord, its upper and lower arms being designated by the characters g_1 and g_5 while curve g_2 sits or rides on the rounded notch 5 in the holder.

The whole principle is also shown in Figure 5; the needle and hook, when the cylinder does not press, are illustrated in full lines, while when pressing occurs, it is illustrated by dotted lines in a shifted position.

The advantages of this hook are, first, the shortness in comparison to the present hook, second, nonfriction, and third, removal of the hook in an instant, as it is held only by 15 the harness weight.

This invention also includes the provision and installation of the needle-safe-guard consisting of the slotted side bars R and cross bars r_3 as plainly shown in Figure 2 20 in side view, and in Figure 3 in plan view, the slotted side bars R being movable lengthwise on the pins passing through the slots r_4 on each side in slot r_1 , the bars in one direction being moved through hook r_1 and 25 passed back through spring r_2 .

In the drawings N designates the side bars or framing of the comber boards n_1 which, for the purpose of the invention, are arranged in forwardly descended step-like order, the slope or angle of descent corresponding to that of the frame K .

It is not essential that the interior mechanism be lubricated, as little, if any, friction occurs therein; bearing in mind that any 35 springs or needles are kept away entirely, it is evident that cylinder has to press with less force and that operation of the machine affords less power, therefore, the pounding is minimized to a slight chatter; 40 there is also no danger of piercing cards with the needles which results in a faulty weave.

I claim:

1. In a jacquard weaving machine of the 45 character described, a jacquard cylinder mounted on pivoted arms to be swung inwardly and outwardly, means for rotating

said cylinder step by step in either direction of rotation, said means comprising a hook to turn the cylinder in a forward direction, a lever and connected arm to turn the cylinder in a reverse direction, and said arm being provided with a curved lifting projection and said hook being formed with a bend with which said projection co-operates to raise said hook and disengage the same from the cylinder through the movement of the arm.

2. A jacquard weaving machine according to claim 1 provided with spring retracting means for withdrawing said arm from engagement with the hook and jacquard cylinder.

3. A jacquard weaving machine comprising a frame for the support of the upper mountings of the machine, above the harness, said frame consisting of side supports connected together by cross bars, and having a forwardly and downwardly sloping upper framing, above which are located the knife frame, and below which are located the needless and comber boards being arranged in forwardly descending step series.

4. A jacquard weaving machine comprising a jacquard cylinder, a series of needles co-operating therewith, and arranged in superposed horizontal groups, the needles varying in length in descending successive groups and terminating at their free ends in reverse bends engaging with the hooks to which the harness ends are attached, a needle board through which the needles pass, hook supports and needle holders below said supports and through which the needles pass.

5. A jacquard weaving machine according to claim 4, provided with a needle guard, comprising slotted side bars and connecting transverse bars, forming guards to limit the thrust of the needles, said needle guard being movable in one direction by the thrust of the needles and reversely by spring pressure.

ALOIS PIVETZ.
